UNITED STATES PATENT OFFICE

CARL GREY SNAVELY, OF LEWISBURG, PENNSYLVANIA

BODY-PROTECTING SHIELD

Application filed June 20, 1929. Serial No. 372,465.

My invention relates to protective apparel for athletes and more particularly to improvements in apparel having shields or guards of rigid material for affording greater protection to certain parts of the wearer's body.

A protective device embodying my invention is especially adapted for use by athletes such as football players wherein it is desired to protect those parts of the body which are most liable to painful and serious internal injury.

The primary object of my invention is to provide protective apparel in which rigid form fitting arched shape guard members shall effectively shield designated portions of the wearer's body.

Another object of my invention is to provide a body shield of the character designated which shall also serve as a convenient support for holding the athlete's uniform in position so as to prevent the same from becoming disarranged and chafing the body during the player's activity.

A further object of the invention is to provide a protective belt having rigid guard members which may be adjusted relative to the belt so that the same protective device may be worn by persons having a different size and shape.

A further object of the invention is to provide form fitting protective apparel of the character designated which shall be entirely concealed and thereby provide a football player's uniform of neater appearance than present apparel now in use.

These and other objects of the invention will be more apparent by reference to the accompanying drawing and description and specifically set forth in the claims.

In the drawing:

Figure 1 is a plan view of a protective shield employing guard members constructed and arranged in accordance with the present invention;

Figure 2 is a plan view of one of the guard elements;

Figure 3 is a section on line 3—3 of Figure 2;

Figure 4 is a section on line 4—4 of Figure 2;

Figure 5 is a view in elevation of the guard element shown in Figure 2;

Figure 6 is a perspective view of the guard element;

Figure 7 is a modification of the protective shield in which additional guard elements are employed;

Figure 8 is a view in elevation of the shield shown in Figure 1;

Figure 9 is a detail view in section on line 9—9 of Figure 1;

Figure 10 is a view showing the application of the shield to the wearer's body and supporting the trousers;

Figure 11 is a similar view showing the application of an additional guard member; and

Figure 12 is a view in elevation of the guard element shown in Figure 11.

My invention contemplates providing protective apparel having rigid arch shaped guard members which shall be particularly adapted for use by football players as the nature of the game of football is such that the players frequently become disabled by serious injuries inflicted to the hips and kidney portion of the body. The region of the kidneys is a very sensitive part of the body and many times a serious internal injury results from a relatively light blow on that portion of the body because the infection spreads inwardly. An injury to the ilium or hip bone is not particularly serious, but it is a very painful injury and slow in healing and therefore a player receiving such an injury at the beginning of the football season is often prevented from again playing the game for a long time.

In the illustrated embodiment of my invention, shown in Figs. 1, 2, 3, 4, 5 and 6, rigid arch shaped, or spheroid guard members 10 are secured to a belt 11 of padded material which encircles the player's waist. These arch shaped members are preferably in the form of the segment of a hollow sphere and extend horizontally on the belt to which they are attached. This belt may be made of felt, kapok, soft rubber or any other form

of flexible form fitting cushioning material which shall closely fit the body. The belt is covered with a non-stretchable fabric 12 so as to prevent stretching of the belt when secured to the person. The ends of the belt are connected by lacings 13 or straps 14 as shown in Figures 7 and 8. These arched guard elements 10 are made of any suitable rigid or semi-rigid material such as light metal, leather or fiber and are attached to or incorporated in the belt so as to cover the extremities of the hip bones and protect the kidneys by bridging over the region of these delicate portions. The guards 10 being in the form of a sector of a hollow sphere, have a base configuration which is curved so as to fit the wearer's body, and any serious injury to these parts is effectively reduced to a minimum by preventing a direct blow to these parts by dissipating the force to the less sensitive parts of the body.

The guard elements 10 are secured to the belt by placing the same between the cushion material 11 and the outer fabric covering 12 as shown in Figure 9 and then stitching the materials around the base edge of the guard to hold it in the desired position on the belt. This manner of securing the arch shaped guards on the belt enables the protective apparel with the rigid guard members, to be fitted to the body so that the athlete may have the free and natural use of the body without the annoyance and inconvenience of bulky protectors now in use.

I am aware that protective apparel employing arch shaped guard elements has heretofore been embodied in a football player's uniform for protecting the head and shoulder of the person, but my invention is directed to a hip and kidney shield employing these elements and which shall also serve as a support for holding the player's other garments, such as the jersey and trousers, in proper relation.

The invention further contemplates providing a protective belt in which the guard elements may be adjusted relative thereto so that the same belt may be worn by persons of different size and shape. This result is accomplished by providing the belt with guard pockets 15 of larger size than the guard elements, and when the belt is fitted to the body, the guards are then inserted in the pockets and located therein relative to the player's body so as to comfortably fit the wearer as shown in Figures 7 and 8. The guards thus being properly positioned, they are then secured in place by stitching around the base as heretofore described. If it is desired to provide the belt with guard elements which may be temporarily adjusted while the player is in action, the pockets are provided with eyelets 14' and lacings 15'.

To provide for further protection to the

player's limbs the belt 11 may be provided with flexible extensions 16 depending from the lower edge of the belt. These extensions are also made of suitable cushion material and may be provided with pockets for guard elements as heretofore described.

The guard elements 10 may also be provided with a fabric rim 17 which shall better enable the guards to be attached to the padded material. This rim may also form a cushion if it is desired to attach the guards directly to the body of the wearer by straps or adhesive tape 18 as shown in Figs. 11 and 12.

The belt is also provided with separate rigid guard members 19 for protecting the back and spinal column of the body, and these members may also be of a shape to comfortably fit the body of the wearer.

Another important feature of my invention is to provide a shield which shall hold the player's uniform in proper position by supporting the wearer's trousers and upper garment or jersey in proper position relative thereto so that the uniform may be comfortable at all times and eliminate the usual annoyance experienced by athletes in apparel of this character when the same becomes wet and disarranged during the player's activity. The relation of the player's belt 11, jersey 20 and trousers 21 is shown in dotted lines in Fig. 10. This arrangement of supporting the player's trousers by means of the protective belt enables the trousers to cover and conceal the guard members and thereby provide a neat appearing uniform. The trousers, shield belt and jersey forming separate units, the lower portion of the jersey is secured by the waistband of the trousers engaging the rigid protruding portions of the shield. This manner of inserting the player's jersey between the guard elements and the waistband of the trousers provides an effective means for preventing the player's clothing from shifting to uncomfortable positions when the player is in action, as the belt 11 is the only member which is secured to the body of the wearer.

The important feature of this arrangement of the player's uniform is that the guard members firmly hold the trousers and prevent them from slipping downwardly and binding the hips of the player and hinder his activity. Furthermore, the waistband of the trousers binds the jersey on the rigid guard members and prevents the lower extremity of the jersey working upward and becoming separated from the trousers and exposing the player's body. This arrangement of clothing has the further advantage that the guard members are entirely covered by the player's apparel so as to provide a neat appearing uniform which is free from all loose clothing.

The presence of loose clothing and external shields frequently enables an opposing player to catch hold of these garments and stop the

player. A shield embodying my invention enables a football player to equip himself with a neat appearing uniform which shall be more efficient than uniforms now in use and which shall have guard members constructed and arranged to reduce individual injuries to a minimum.

While I have shown preferred embodiments of protective apparel having guard members constructed and arranged in accordance with my invention, it is obvious that various changes may be made therein without departing from the spirit of the invention as set forth in the claims.

15 What I claim is:

1. A body protective apparel comprising a hip belt of flexible cushion material, rigid hollow spheroidal sector shaped guard members positioned on said belt so as to cover the 20 hip portions of the body, means for securing the guard members to the belt, the base edges of said members being curved to engage the cushion material and conform to the shape of the body at the hips and means for securing the belt to the body.

2. In protective apparel of the character described, a hip belt of flexible cushion material, rigid spheroidal sector shaped guard members positioned on the belt so as to cover the hip portions of the body, pockets formed in the belt for accommodating individual guard members and means for securing the individual guard member in its pocket.

3. In protective apparel of the character described, a hip belt of flexible cushion material, rigid spheroidal sector shaped guard members positioned on the belt so as to cover the hip portions of the body, pockets formed in the belt for accommodating individual guard members and means for drawing the pocket closed.

4. In protective apparel of the character described, the combination with a hip belt of flexible cushion material, of rigid hollow spheroidal sector shaped guard members positioned thereon, the major axes of the guard members extending horizontally on the belt so as to cover the hip portions of the body, the base edges of the member being curved so as to conform substantially to the shape of the body at the hips, and means for securing the guard members to the belt whereby the cushion material shall conform to the base edges of the guard members.

5. As an article of manufacture, a hip belt of flexible cushion material, rigid spheroidal sector shaped guard members positioned thereon, the major axes of the guard members extending horizontally on the belt so as to cover the hip portions of the body, means for securing the guard members to the belt whereby the cushion material shall conform to the base edges of the guard members, thigh pads 65 depending from said belt and spheroidal sec-

tor shaped guard members also extending horizontally on said pad.

6. In protective apparel of the character described, the combination with a pair of football trousers, of a hip belt underlying the 70 waist portion of the trousers, rigid spheroidal sector shaped guard members positioned on the belt, the major axes of the guard members extending horizontally on said belt so as to cover the hip portions of the body and support the trousers, means for securing the guard members to the belt whereby the cushion material shall conform to the base edges of the guard members and means for securing the belt to the body of the wearer.

75 In testimony whereof I affix my signature.
CARL GREY SNAVELY.
